(57) **CLAIM**

The ornamental design for a dresser and mirror, as shown and described.

DESCRIPTION

FIG. 1 is a front elevational view of a dresser and mirror showing my new design, with the louvered cabinet doors closed.

FIG. 2 is a rear elevational view thereof.

FIG. 3 is a right elevational view thereof, with the left elevational view thereof being a mirror image.

FIG. 4 is a top plan view thereof.

FIG. 5 is a bottom plan view thereof.

FIG. 6 is a front elevational view of the dresser and mirror of FIG. 1 showing my new design, with the louvered cabinet doors open.

FIG. 7 is a rear elevational view thereof.

FIG. 8 is a right elevational view thereof, with the left elevational view thereof being a mirror image.

FIG. 9 is a top plan view thereof; and,

FIG. 10 is a bottom plan view thereof.

The broken line showing of drawer pulls in FIGS. 1 and 6 forms no part of the claimed design.
